UNITED STATES PATENT OFFICE.

ARTHUR E. JOHNSON, OF TAFT, CALIFORNIA.

OIL-WELL CEMENT-DUMP BAILER.

Application filed May 11, 1927. Serial No. 190,462.

My invention is in an oil well cement dump bailer or the like to be used in cementing off a deep well, such as an oil well.

An object of my invention is the construction of a well cement dump bailer for deep wells, such as oil wells, in which the cement is conveyed to the bottom of the well by means of a bucket or column of pipe.

A more specific object is the construction of a bottom dumping bailer which is provided with a mechanism to cause the bottom to dump when the base of the structure strikes the bottom of the well or other suitable obstruction such as a bridge.

In constructing my invention I utilize a pipe or a string of piping, and to the base of this piping I attach a bucket having a bottom dumping trap, this trap being held closed by a latch. Slidably mounted on the bucket is a sleeve and in the lowermost position of such sleeve the latch is locked closed, holding the trap in its closed position. When the sleeve strikes the bottom of the well or an obstruction, it is forced upwardly, releasing the latch and allowing the trap to dump, thereby discharging the cement.

My invention is illustrated in the accompanying drawings, in which:

Figure 1 is a vertical longitudinal section through my well cement dump bailer, illustrating same in the closed position for carrying the cement to the position of dumping.

Figure 2 is a section similar to Fig. 1, showing the bailer in the dumping position with the trap open, the sleeve elevated, and the latch released.

Figure 3 is a vertical section taken on the line 3—3 of Fig. 2 in the direction of the arrows.

Figure 4 is a horizontal section on the line 4—4 of Fig. 1 looking upwardly in the direction of the arrows.

A suitable pipe or pipe string is indicated by the numeral 11 and this is connected to a cement bucket, designated generally by the numeral 12, there being a screw threaded coupling 13 between the lower end of the pipe and the upper end of the bucket. The main body of the bucket is of reduced diameter over that of the connection or coupling, as indicated by the parts having the numbers 14 and 15. A trap 16 is secured to the open lower end 17 of the bucket by means of a pivot pin 18 connecting ears 19 on the trap with a

lug 20 which has a screw threaded stem 21 55 threading in the base of the bucket.

On the outside wall of the bucket, preferably opposite the lug 20, there is a longitudinal groove 22, and at the upper part of this groove, a recess 23. In this groove is fitted a latch 24 which has a head 25 seated in the recess, this being a loose seat and allowing the latch to have a lateral movement, such latch having a catch 26 at the lower end, this having a rounded nose 27 to be thrust outwardly by the cammed edge 28 of the trap.

A sleeve 29 is slidably mounted on the main body structure of the bucket, sliding on the surface 14 and being guided by studs 30 which are screw threaded into the body portion of the bucket and operate in slots 31 of the sleeve, this action limiting the movement of the sleeve upwardly and downwardly and the connection being sufficiently loose so that the sleeve normally hangs in the position shown in Fig. 1. On the side of the sleeve adjacent the latch is an elongated slot 32, this being of sufficient size to allow the latch 24 to project therethrough or partly therethrough in the dumping of the bucket, as 80 hereunder set forth.

The manner of functioning and using my bucket is substantially as follows:

With the bucket at the surface of the well the trap 16 is closed and is held in its closed position by the latch 24, the catch 26 preventing its opening, and the latch being prevented from movement by the wall of the sleeve 29 when such sleeve is depending in a position as shown in Fig. 1. The pipe 11 in the bucket may then be filled with cement to the desired extent and the whole lowered in the well. When the lower edge of the sleeve strikes the bottom of the well, or some obstruction such as a bridge, the sleeve is forced upwardly into the position shown in Fig. 2, this sleeve sliding on the studs 30 which have relative movement in the slots 31. This upward sliding of the sleeve brings the elongated slot 32 into registry with the latch 24. This allows the latch to swing outwardly as shown in Fig. 2, the actuating movement to shift the latch being due to the cam edge 28 of the trap and the curved surface 27 of the catch portion 26 of the latch. The latch is allowed to swing on the head 25, which fits in the recess 23. Therefore, when the trap is opened, as illustrated in Figs. 2 and 3,

the cement drops by gravity, filling the well as desired. The bucket may then be drawn upwardly and, although the sleeve will then drop to the position shown in Fig. 1 pressing 5 the latch inwardly, the trap 16 will still be left open and the operation may then be repeated.

Various changes may be made in the principles of my invention without departing 10 from the spirit thereof, as set forth in the description, drawings and claims.

I claim:

1. A well cementing device comprising in combination a bucket structure, a dumping 15 trap pivotally mounted within said bucket, a latch shiftably mounted on the bucket structure to engage the trap, a sleeve slidably mounted on the bucket structure adapted in its lowest position to hold the latch in locking 20 relation to the trap, said sleeve releasing the latch in its upper position.

2. A well cementing bucket comprising in combination a bucket structure, a dumping trap pivotally mounted within said 25 bucket, a latch shiftably mounted on the outside surface of the bucket structure, a sleeve slidably mounted on the bucket structure, the sleeve engaging the latch in its lowest position and retaining the latch to lock the trap 30 closed, the sleeve having an opening to allow movement of the latch when the sleeve slides to an upper position, and hence allow dumping of the trap.

3. A well cementing bucket comprising in combination a bucket structure having a pivotally mounted trap at its lower end, a latch shiftably mounted in the outside wall of the bucket structure, a sleeve slidably mounted on the exterior of the bucket structure, 40 means to guide and restrict the movement of the sleeve, the sleeve in its lowest position engaging the back of the latch whereby the latch may hold the trap in closed position, said sleeve having an opening to allow outward movement of the latch when in its upper position whereby the trap may be released and opened.

4. A well cementing bracket comprising in combination a tubular bucket having a pivoted trap at its lower end, the bucket having 50 a longitudinal groove on its outer surface, a latch fitting in said groove and having a catch to hold the trap closed, a sleeve slidably mounted on the bucket, said sleeve in its lower position engaging the back of the latch to

prevent its movement from a locking position, and in its upper position allowing swinging outwardly of the latch to release the trap.

5. A well cementing bucket comprising in combination a tubular bucket structure having a pivotally mounted trap at its lower end, there being a longitudinal groove on the outside of the bucket structure with a recess at the top of the groove, a latch having a head fitting loosely in the recess, the main portion of the latch fitting in the groove, and having a catch at its lower end to engage the trap, a sleeve slidably mounted on the outside of the bucket structure, with means to guide and restrict the movement of said sleeve, the sleeve in its lowest position engaging the back of the latch to hold the trap locked, and in its upper position allowing outward movement of the latch.

6. A well cementing bucket, as claimed in claim 5, the sleeve having an elongated slot in one side adjacent the latch to allow outward swinging of the latch into said slot in the upper position of the sleeve.

7. A well cementing bucket comprising in combination a tubular bucket structure having a pivotally mounted trap at its lower end, the bucket structure having a groove in one side with a recess at the upper end of the groove, a latch having a head, the head loosely fitting in the recess and the main portion of the latch in the groove, the latch having a catch at its lower end to engage the trap, a sleeve having a plurality of opposite slots, pins extending through said slots and connected to the bucket structure to guide and limit the sliding movement of the sleeve, the sleeve in its lowest position engaging the back of the latch whereby the trap may be held locked, there being an elongated slot adjacent the latch to allow outward swinging thereof with the sleeve in the upper position to allow release of the trap by the latch.

8. A well cementing bucket, as claimed in claim 7, the latch having a curved nose structure, and the trap having a cammed surface engaging such nose structure whereby on release of the back of the latch by the upward movement of the sleeve the trap is forced downwardly by the weight of material thereon.

In testimony whereof I have signed my name to this specification.

ARTHUR E. JOHNSON.
